UNITED STATES PATENT OFFICE.

ANDREW L. WEIS, OF MONROE, MICHIGAN, ASSIGNOR TO THE WEIS' FIBRE CONTAINER CORPORATION, OF MONROE, MICHIGAN, A CORPORATION OF SOUTH DAKOTA.

PAPER BOX OR SIMILAR CONTAINER.

Application filed November 12, 1918. Serial No. 262,146.

To all whom it may concern:

Be it known that I, ANDREW L. WEIS, a citizen of the United States of America, and a resident of Monroe, Michigan, have invented 5 a certain new and useful Improvement in Paper Boxes or Similar Containers, of which the following is a specification.

This invention relates to paper boxes of that kind in which the entire box, preferably, is made from a single blank having foldably connected sections to form the side walls, and flaps to form the top and bottom.

Generally stated, the object of the invention is to provide a box which can be shipped flat, and which can be readily reduced to a condition suitable for use by the folding and securing in place of the flaps which form the bottom, so that the box can be filled with tobacco or some other commodity, and which can then be readily closed by securing the upper flaps in place, the lower flaps being practically locked against opening, after the bottom is once closed, but the other flaps being capable of unfolding to open the top of the box when it is desired to remove the contents thereof.

It is also an object to provide certain details and features of construction tending to increase the general efficiency and the desirability of a box of this particular construction.

To these and other useful ends the invention consists in matters hereinafter set forth and claimed, and shown in the accompanying drawings, in which—

Fig. 1 is a perspective of a box embodying the principles of the invention, showing the top thereof open.

Fig. 2 is a vertical section on line 2—2 in Fig. 3.

Fig. 3 is a vertical section on line 3—3 in Fig. 2.

Fig. 4 is a horizontal section on line 4—4 in Fig. 2.

Fig. 5 is a plan of the blank from which said box is made.

Fig. 6 is a perspective of the lower portion of a similar box, showing the bottom flaps only partially closed or folded, and illustrating this form of the invention.

Fig. 7 is a similar view showing another form of the invention.

Fig. 8 is a horizontal section on line 8—8 in Fig. 6.

Fig. 9 is a horizontal section on line 9—9 in Fig. 7.

As thus illustrated, and referring to Fig. 5, it will be seen that the blank from which the box is made comprises the rectangular sections 1, 2, 3, 4, 5, and 6, which are flexibly connected together by the creases or score lines 7, 8, 9, 10 and 11, the sections 1, 2 and 4 being broad to form the front and back of the box, while the sections 3 and 5 are narrow to form the narrow sides of the box. The section 1 has a half-moon-shaped opening 12 therein, near its lower edge, and said lower edge has a flap 13 secured thereto along the flexible crease or score line 14, 70 while the section 2 has a curved slot 15 therein near its upper edge. The section 3 is provided with upper and lower flaps 16 and 17, and the section 5 has upper and lower flaps 18 and 19, while the section 4 75 has upper and lower flaps 20 and 21; and the flaps 16, 18 and 20 are connected to their respective sections along the crease or score line 22, while the flaps 17, 19 and 21 are connected to these sections along the score line 80 23, so that the flaps may be folded as hereinafter described. For the purpose of closing the top of the box, as hereinafter explained, the flap 20 has a crease or score line 24, and for the same purpose the flap 21 has 85 a crease or score line 25, and in addition the flap 21 is cut through at 26, and in this way the half-moon-shaped portion 27 can be pressed slightly inward, so that it will cooperate with the opening 12, in the manner 90 hereinafter set forth.

With a blank of the foregoing character, the box is made in the factory to the extent that the blanks are formed and partially set up or put together, the sections 1 and 2 95 being folded flatwise together, and the free edge of the section 1 being glued or otherwise secured along the inner surface of the section 2 adjacent the fold line 8, so that the sections provide a double wall; 100 the section 6 is then glued or otherwise secured to the section 1 along the fold line 7, whereby a box which is flat and rectangular in cross-section is provided. The hollow structure thus formed, however, can 105 be flattened down when in this condition, which will reduce the expense of transportation. The user will then open it up, fold the flaps 17 and 19 upward, fold the flap 13 upward against the flaps 17 and 19, 110

and then fold the flap 21 upward and insert its edge between the outer wall 2 and the inner wall 1, this flap being folded along the line 25 where it engages the lower edge of the wall 1, whereby the bottom is closed. The portion 27 having been displaced inwardly, its straight edge will drop into the space formed by the opening 12 and will engage the straight edge of the latter, thus forming a locking device to hold the bottom flaps in closed position. As the walls 1 and 2 are held flatwise together, the interlocking flap 21 cannot be withdrawn except by forcibly pulling it out, which would tear the paper, or by squeezing the box in a manner to spring the walls 1 and 2 apart sufficiently to disengage the portion 27 from the opening 12, so that the bottom or lower end of the box 20 is practically closed permanently after the flaps are properly folded. This, however, leaves the top of the box open, and the tobacco or other commodity can then be placed therein. After that, the flaps 16 25 and 18 can be folded downward, and the flap 20 can be folded downward, so that it will bend along its crease or score line 24 where it engages the upper edges of the walls 1 and 2, and the tongue-shaped portion of the flap 20 can then be inserted downwardly through the slot 15 and between the walls 1 and 2 to close the top of the box. However, the tongue portion of the flap 20 can be withdrawn from the slot 15 when it is desired to open the box for the purpose of removing the contents thereof.

In Fig. 6 the construction is similar to that previously shown, except that the 40 lower closing flap 28 of the box is provided with two tongue-shaped portions 29 pressed from the body portion thereof, which are adapted to engage the rectangular openings 30 formed in the inner wall 45 31, which latter corresponds to the inner wall 1 of the construction previously described. In this way, the tongues or small flaps 29 cooperate with the openings 30 to practically permanently close the bottom of the box. In Fig. 7 the construction is similar to that previously described, but in this case the opening 12 previously described is 50 engaged by a corrugated tongue or inwardly displaced portion 32 which is pressed from the body portion of the flap 33, which latter corresponds to the flap 21 previously described.

Other modifications will be obvious, but in any event the box, as one feature of the 60 invention, is adapted to be shipped flat, after the blank is partially folded, and is provided with bottom flaps which can be folded to interlock to close the bottom, and with top flaps which can also be folded to 65 close the top after the tobacco or other com-

modity is placed in the box. Thus a saving in transportation is accomplished, as the boxes can be packed tightly together without any waste space.

Thus it will be seen that the flap 28 or 70 the flap 33 or the flap 21, in each form of the invention, has an interlocking connection with the inner thickness of a twoply or double thickness wall, so that the catch, or interlocking connection thus formed is 75 inaccessible from the outside of the box, whereby this interlocking connection cannot be disturbed after the box is filled, the bottom of the box being practically closed permanently in this way. 80

What I claim as my invention is:—

1. In a box, an outer wall, an inner wall, the inner wall having an opening which is covered externally of the box by the outer wall, a closing flap for insertion between 85 the two walls, and means on the flap to engage said covered opening to form a catch which is inaccessible from the outside of the box thereby to hold the flap closed, together with other elements to form the balance of 90 the box.

2. A structure as specified in claim 1, said means comprising a portion having a straight edge pressed inward from the flap, and the two walls being flatwise together, so 95 that the outer wall holds said edge in engagement with a straight edge of the opening.

3. A structure as specified in claim 1, and a plurality of flaps held together by said closing flap, forming the bottom of the box, 100 said walls forming one side of the box, and other walls forming three other sides of the box, together with a slot in said outer wall, and means including a flap for insertion through said slot and between the inner and 105 outer walls to close the top of the box.

4. A structure as specified in claim 1, said box being formed from a single blank, and said walls being adjacent rectangular sections of said blank, with a straight fold line 110 between the two sections, and said blank having means secured to the inner wall along the edge thereof adjacent said fold line, the other edge of the inner wall being secured to the outer wall, and said flap being flexibly connected to another section of said blank. 115

5. A box composed of a blank partially folded to form the sides thereof, but having top and bottom flaps which are left unfolded at opposite ends of the box to permit the shipment thereof in a flattened-out condition, the bottom flaps being adapted to fold into position to permanently close the bottom, preparatory to filling the box, with inaccessible structural provisions concealed within the front wall of the box to hold the bottom flaps in place, so that the bottom cannot be opened, and the top flaps being adapted to fold into position to close the box to 120 125 130 135 140

that it can be opened after the filling thereof.

6. A structure as specified in claim 5, said structural means of the bottom flaps including a flap with an interlocking portion, said box having a side wall provided with means for engaging said interlocking portion, so that the bottom is practically permanently closed, but the upper flaps being adapted to be easily unfolded to open the box.

10. 7. In a box blank, the combination of rectangular blank sections (1 or 31, 2, 3, 4 and 6) to form the sides of the box, top flaps to close the top of the box, having a slot in one section (2) for engaging one of said flaps, and bottom flaps to close the bottom of the box, one of the bottom flaps (21 or 28 or 33) having interlocking means, and one side section (1 or 31) having an opening with a straight edge to engage said interlocking means, with an outer thickness of sheet material covering said opening and means engaging therein, so that the interlock thus formed is inaccessible from the outside of the box, substantially as described.

25. 8. In a box made from a single foldable blank of sheet material, the combination of an outer side wall forming one section of said blank, an inner wall disposed flatwise against said outer side wall and also forming part of said blank, one edge portion of said inner wall being secured to the outer

wall, means for insertion between the two walls for interlocking connection to the inner wall for closing one end of the box, so that this end after being thus closed cannot be 35 opened after the box is filled, and other elements forming the balance of said blank to complete the box, whereby the box can be opened and closed.

9. A structure as specified in claim 8, said 40 inner wall and the means for insertion between the two walls having interlocking provisions to keep said end of the box permanently closed.

10. A structure as specified in claim 8, said 45 outer wall having a slot therein, and one of said elements of the blank consisting of a closure flap having a tongue portion for insertion through said slot and into the space between said outer wall and said inner wall 50 and thus forming the means whereby the box can be opened and closed.

11. In a box, an outer wall, and an inner wall formed with interlocking means disposed flatwise against the inner surface of 55 the outer wall, with the edges of the inner wall secured in place so that another element of the box can be inserted edgewise between the two walls for interlocking connection to the inner wall to permanently close one end 60 of the box.

ANDREW L. WEIS.
